PORTABLE BODY WARMER

Reuben Robert Reveno, Philadelphia, Pa.

Application February 23, 1942, Serial No. 431,998

6 Claims. (Cl. 126—204)

This invention relates to body warmers of a portable type for supplementing clothing to protect the wearer (particularly the lower part of the body) from cold, and intended for use by spectators at out-door sporting and field events such as football games, ice hockey, races, etc., or as protective covering for invalids, convalescents, etc., requiring warmth for their bodies while sitting out-doors. 5

10
Amongst the objects of my invention are to enlarge upon the usefulness of devices of the kind referred to and to enhance their efficiency from the standpoints of heat conservation and economy of operation.

Further aims of my invention are to attain the foregoing advantages in a body warmer which is simple in construction and light in weight; which is easily and quickly applied or removed; which can be manufactured at small expense; and which can be folded into a small and compact package for convenience of ready carriage.

Other objects and attendant advantages will appear from the following detailed description of the attached drawings, wherein Fig. 1 is a perspective view showing my improved body warmer collapsed in readiness to be carried about.

Fig. 2 shows the device set up in readiness for use.

Fig. 3 shows how the body warmer is actually used with the wearer sitting.

Fig. 5 is a plan view of the base portion of the device with portions of the covering cut away; and

Figs. 6 and 7 are longitudinal and cross sectional views taken as indicated respectively by the angled arrows VI—VI and VII—VII in Fig. 4.

From these illustrations it will be seen that my improved body warmer includes a substantially flat rigid base 1 of composite construction having in this instance a rectangular foundation frame 2, which may be of wood or other thermo-insulating material, and which is braced by corner pieces shown at 3 in Fig. 5. Set apart within the frame 1 at the center is a sub-division or well 4 which is defined by transverse frame strips 5 and a lengthwise connecting strip 6. The hollows of the frame 1, except for the sub-division or well 4, are filled with loose thermo-insulation 7 such as rock-wool or the like, which is conventionally indicated and which is retained by top and bottom asbestos sheets 8 and 9 whereof the upper one stops short of said well. The

parts constituting the base are covered with textile material, preferably tough canvas or deck-cloth indicated at 10. The well 4 is lined with non-corrosive sheet metal 11, said lining bearing at the bottom upon a pad 12 of insulation, and extending between opposite sides thereof slightly above its bottom are spaced rods 13 which serve as a false floor to support a heating element or unit 15. As shown, the heating unit 15 is in the form of a porous bag filled with a suitable granular chemical substance or compound which gives off heat for a considerable period when wetted, depending upon the amount of moisture applied thereto. Other types of commercial heating units may of course be substituted, if desired, within the scope of the appended claims. The well 4 is provided with a reticulate grid-like cover 16 which may be formed from relatively stiff perforated sheet metal, also preferably of a non-corrosive kind, said cover being attached by hinges 17 along one edge so that it can be readily swung up for access to the recess or well 4 when replacements of the heating element or unit 15 are necessary.

25 My improved body warmer further includes an envelope 18 which may be of any flexible material which is air-tight and moisture-repellent and which is secured at its lower edge peripherally of the base 1. As shown in Fig. 2, the
30 envelope 18 is vertically slitted at the front and the slit edges are separably securable by a conventional form of slide fastener whereof the lug tapes are indicated at 19 and the slide at 20. The envelope 18 is provided with a hem 21 around
35 the greater portion of its top edge with segments 22 containing elastic to the ends of which, belt tongues 23 and 24 are secured, one such tongue being provided with a buckle 25 and the other
40 with perforations for receiving the tongue of said buckle. By this means it will be apparent that the upper edge of the envelope 18 may be snugly fastened about the body of the wearer as shown in Fig. 3. The envelope 18 is moreover
45 provided at the front with openings 26 having inward sleeve-like extensions 27 whereof the end edges are hemmed as at 28 and contain elastic for capacity to contract snugly around the wrists of the wearer.

50 The bottom of the base 1 is finished with a covering 30 of leather or imitation leather, and a perimetric band 31 of the same material overlaps the attached lower edge of the envelope 18; and said base is moreover provided at corners with pads or feet 32 by which it is supported at a

55

slight elevation from the ground when the device is in use.

The material from which the envelope 18 is formed is sufficiently thin to allow of being compactly folded into the confines of the base area, as shown in Fig. 1, and a cover 33 of leather or artificial leather is provided to confine it, said cover being permanently secured along one of the longitudinal edges of the base. Any convenient means may be employed for detachably securing the other three edges of the cover, for example, a slide fastener of which the lug tapes are indicated at 35 and the slide at 36 in Fig. 1. For convenience in carrying the body warmer, I have provided it with a handle 37 which is attached to the other longitudinal edge of the base at the center.

From the foregoing, it will be seen that I have provided a simple and inexpensive body warmer which is light and compact when folded so that it can be readily carried about. By reason of the construction of the base from thermo-insulating material and the formation of the envelope 18 from thin, light air-tight material, the device is rendered highly efficient both as regards heat conservation and the cost of operation.

In preparation for use of the body warmer, the base 1 is placed at a suitable distance from the seat S (Fig. 3) which is to be occupied by the wearer, with the envelope 18 opened out. With this preparation, the wearer steps onto the base 1 with her (his) feet resting on the grid 16 over the heating unit 15 (whereto a suitable amount of water was previously applied); whereupon the envelope 18 is drawn up over the legs and lower body, the slide fastener closed, and the belt means 23, 24 drawn tight and buckled. The envelope 18 having thus been placed and secured, the wearer may now sit down as shown in Fig. 3 and thrust her (his) hands into the openings 26. Obviously, by being directly over the heating unit 15, the feet are kept comfortably warm, while the entrained air within the envelope is circulated by convection and heated as it passes through the perforations of the grid 16 and around said unit to keep the legs, the lower body, and the hands warm.

It is to be understood of course that I do not wish to be limited to the precise details of construction herein set forth, nor restricted to the use of the specific form of heating unit herein shown and described by way of example, since other types of heating units may be substituted within the scope of the appended claims.

Having thus described my invention, I claim:

1. A body warmer comprising a flat rigid base with a well containing a removable heating element or unit; a reticulate lid for the well serving in part as a support for the wearer's feet when the warmer is in use; an envelope of flexible air-tight material attached at the bottom to the base and adapted to be securable about the body of the wearer, said envelope being foldable into the confines of the base area; a cover corresponding in size to the base area for confining the envelope; means for securing the cover in closed position; and a handle for carrying the warmer when collapsed.

2. A body warmer comprising a flat rigid base with a well containing a removable heating element or unit; means within the well for supporting said element or unit with provision for air

circulation around it; a reticulate lid for the well to serve in part as a support for the wearer's feet when the warmer is in use; an envelope of flexible air-tight and moisture-repellent material attached at the bottom to the base and adapted to be secured at the top about the body of the wearer, said envelope being compactly foldable into the confines of the base area; a cover corresponding in size to the base area for confining the folded envelope; means for securing the cover in closed position; and a carrying handle attached to the edge of the base.

3. A body warmer according to claim 2, in which the cover securing means is in the form of a slide fastener whereof the lug tapes are secured respectively to the edges of said base and said cover.

4. A body warmer comprising a substantially flat rigid base of thermo-insulating material having a perimetric foundation frame of light-weight rigid material with cross bars inward of its opposite ends setting apart a well in the center of the base; relatively loose thermo-insulating material filling the hollows at the ends of the frame; rigid top and bottom sheets of compacted insulating material retaining the relatively loose insulating material within said hollows; means within the well of the base for supporting a heating element or unit with provision for air circulation all around it; and an envelope of flexible air-tight and moisture-repellent material attached perimetricaly of the base and adapted to be secured at the top about the body of the wearer.

5. A body warmer comprising a substantially flat rigid base of thermo-insulating material having a perimetric foundation frame of light-weight rigid material with cross bars inward of its opposite ends setting apart a well in the center of the base; relatively loose thermo-insulating material filling the hollows at the ends of the frame; rigid top and bottom sheets of compacted insulating material retaining the relatively loose insulating material within said hollows; a lining of sheet metal within the well; and a layer of thermo-insulating material underlying the lining in the bottom of the well; means within the well of the base for supporting a heating element or unit with provision for air circulation all around it; and an envelope of flexible air-tight and moisture-repellent material attached perimetricaly to the base and adapted to be secured at the top about the body of the wearer.

6. A body warmer comprising a substantially flat rigid base of thermo-insulating material having a perimetric foundation frame of light-weight rigid material with cross bars inward of its opposite ends setting apart a well in the center of the base; relatively loose thermo-insulating material filling the hollows at the ends of the frame; rigid top and bottom sheets of compacted insulating material retaining the relatively loose insulating material within said hollows; feet to support the base at a slight elevation from the ground; means within the well of the base for supporting a heating element or unit with provision for air circulation all around it; and an envelope of flexible air-tight and moisture-repellent material attached perimetricaly of the base and adapted to be secured at the top about the body of the wearer.
